UNITED STATES PATENT OFFICE

2,542,050

CRANKSHAFT TWISTING MACHINE

Alois K. Nowak, Evanston, Ill., assignor to Clearing Machine Corporation, Chicago, Ill., a corporation of Illinois

Application August 5, 1947, Serial No. 766,369

10 Claims. (Cl. 153—78)

1

This invention relates to machines for manufacturing crank shafts for engines, and to the method of manufacturing such crank shafts.

An important object of the invention is to provide a new and improved machine which will operate upon a forged crank shaft to properly twist the crank pins of the shaft and accurately to locate the pins according to the design and type of the crank shaft.

Another and important object of the invention is to provide a novel machine for twisting crank shafts, the machine including upper and lower die members adapted to clamp a forged crank shaft in place and then twist the crank pins of the shaft to locate them properly.

A further object of the invention is to provide a crank shaft twisting machine wherein a lower die member is adapted to receive a forged crank shaft, and an upper die member which is adapted to be brought against the lower die to clamp the crank shaft in place, movable dies being caused to twist the crank pins of the shaft in a predetermined manner for properly locating the crank pins in the final shaft after the upper and lower dies have clamped the shaft.

Still another object of the invention is to provide a hydraulically operated crank shaft twisting machine having upper and lower die members, each of which includes movable and stationary dies to clamp a forged crank shaft in place, the movable dies being rotated in a predetermined manner to twist the crank shaft and properly position the crank pins thereon after the shaft is clamped in position.

A still further object is to provide upper and lower die members, each of which includes movable and stationary dies, the upper and lower dies being complementary and clamp the forged crank shaft in place within the dies; the movable die members being adapted to cause the various crank pins of the crank shaft to be twisted about predetermined axes to position properly the crank pins.

Another object is to provide a crank shaft twisting machine which is hydraulically operated, and which is provided with a single hydraulically operated lever arm, the actuation of which lever arm producing successive twisting operations on the forged crank shaft.

Still another object of the invention is the method of forming or twisting a crank shaft in a predetermined manner according to a predetermined sequence to effect the proper twisting of the shaft and to obtain the pins thereon in proper alignment.

2

Numerous other objects and advantages of the invention will become apparent upon reading the following description taken in conjunction with the accompanying drawings in which:

- 5 Fig. 1 is a front elevational view of a machine embodying the principles of the present invention;
- Fig. 2 is a side elevational view of the machine illustrated in Fig. 1;
- 10 Fig. 3 is an enlarged sectional view through the upper and lower dies of the machine showing the dies in closed position and a forged crank shaft therein;
- 15 Figs. 4, 5, 6 and 7 are diagrammatic illustrations of the successive twisting operations performed upon a crank shaft; Fig. 4 illustrating the original position of the crank shaft; Fig. 5 illustrating the positions of the various crank pins at the end of the first twisting operation; Fig. 6 20 showing the positions of the various crank pins at the end of the second twisting operation; and Fig. 7 showing the positions of the various crank pins at the completion of the final twisting operations;
- 25 Fig. 8 is a vertical sectional view through the machine showing the upper and lower dies in separated position;
- Fig. 9 is a vertical sectional view through the machine showing the upper and lower dies in 30 engagement, and illustrating the position of the various crank pins at the end of the first twisting operation;
- Fig. 10 is a vertical sectional view through the end bracket of the lower die in the position it 35 assumes at the end of the first twisting operation;
- Fig. 11 is a view similar to Fig. 9, but showing the various parts of the dies, and the positions of the crank pins, at the end of the final twisting 40 operation;
- Fig. 12 is a view similar to Fig. 10 showing the position of the various parts at the end of the final twisting operation; and
- Fig. 13 is a vertical sectional view through the 45 machine at the end of the twisting operation with the upper and lower dies separated; said view also showing a twisted crank shaft being ejected from the machine.
- The crank shaft twisting machine of the present invention is particularly directed to the twisting of a 6-pin crank shaft having three throws, as distinguished, for example, from crank shaft twisting machines heretofore designed for shafts having four pins. The problems encountered in 50 a crank shaft having three throws are much

more difficult to overcome than crank shafts having a lesser number.

The present invention comprises, in general, a hydraulically operated machine having upper and lower dies. A forged crank shaft is adapted to be placed in a lower die where certain of the bearings thereon are clamped and held against movement. The upper die is brought downwardly against the lower die and is complementary therewith so that the crank shaft may be held in place in its entirety. The upper and lower dies consist of a stationary die, inner rotating dies and outer rotating dies. A single hydraulically actuated lever arm is fastened to the inner rotating dies, and a system of interlocks is provided so that a single stroke of the lever arm will rotate the inner and outer rotating dies successively to perform the necessary twisting operations upon the crank shaft.

The machine illustrated herein, Figs. 1 and 2, is of the portable type, capable of being moved from place to place, although the operation of the machine, and the invention embodied therein, is applicable to a stationary machine as well.

A bed 1 is provided at the lower part of the machine, and this bed has uprights 2 extending upwardly therefrom, a crown 3 being provided at the top of the uprights. A slide 4 is adapted to reciprocate vertically in guideways 5 by any suitable control of a hydraulic fluid from a cylinder 6. The hydraulic fluid is forced to flow through the various conduits provided therefor by means of a pump 7. Any suitable hydraulic system may be utilized for causing operation of the machine, and since the hydraulic system per se forms no part of the present invention, the system is not being illustrated herein in detail.

A lower die member 8 is positioned on the bed 1, and an upper die member 9 is carried by the slide 4.

A forged crank shaft is placed in the lower die 8 after which the upper die 9 is brought into contact therewith and the twisting operation is begun. The lower die 8 comprises a stationary die 10 and outer rotating dies 11 and 12. These outer rotating dies 11 and 12 are provided with pivot pins 13 and 14 respectively on which these dies rotate. Fig. 3 illustrates a sectional view through the two die members 8 and 9 in their closed position, and shows the crank shaft in plan.

Several pairs of rollers 15, 16, 17 and 18 are mounted rotatably on the bed 1, and below the lower die 8 on which the lower curved surface of the lower die may rest to facilitate the rotation thereof during the twisting operation.

Each of the outer rotating dies 11 and 12 is provided with an outer upwardly extending portion 19 through which a pin 20 extends for the purpose of supporting a twisting die 21 for the end bearings of the crank shaft. An end bearing locating lever 22 is secured to the uprights 2 at each end of the lower die member. The inner rotating dies 23 and 24 are located within the outer rotating dies 11 and 12.

The upper die member 9 includes inner rotating dies 25 and 26 which are adapted to cooperate with the inner rotating dies 23 and 24 of the lower die member when the upper and lower die members are brought together during the twisting operation. The upper die member 9 also includes outer rotating dies 27 and 28 which cooperate with the outer rotating dies 11 and 12 of the lower die member 8 during the twisting operation. A stationary die 29 also is located

in the upper die member 9. The stationary dies 29 and 10 then cooperate, and act as holding members when the upper and lower dies 9 and 8 are closed.

A crank shaft having all of the bearings and crank pins thereof in the same plane is placed in the lower die 8 when the two dies are separated, or open. The crank shaft which is to be operated upon by the twisting machine of the present invention consists of three main bearings and six crank pins. The two end bearings of the crank shaft are indicated by the numerals 30 and 31, and the center bearing is indicated at 32. The six crank pins of the crank shaft are indicated in Fig. 3 by the numerals 33, 34, 35, 36, 37 and 38. Four crank pins 33, 35, 36 and 38 are all in alignment before the twisting operation is begun, the other two crank pins 34 and 37 also being in alignment. The crank shaft is placed in the die in such a way that the center bearing 32, and the two intermediate crank pins 35 and 36, are disposed in the stationary die or holding member 10. When the upper and lower dies are brought together, the holding member 29 in the upper die 9 will cooperate with the holding member 10 in the lower die 8 to hold the crank pins 35 and 36 and the center bearing 32 against movement.

The outer crank pin 33 will be clamped between the rotating die or twisting member 23 in the lower die 8, and the rotating twisting member 25 of the upper die 9. Likewise, the other outer crank pin 38 will be clamped between the rotating twisting member 24 of the lower die 8 and the rotating twisting member 23 of the upper die 9. These rotating twisting members 23, 25 and 24, 26 may be referred to conveniently hereinafter as the inner rotating twisting members. The other two crank pins 34 and 37 will be disposed respectively in the outer rotating twisting members 11 and 27, 12 and 28.

When the crank shaft is first placed in the lower die 8, the end bearings 30 and 31 will not be received within their respective twisting dies 21, but will be twisted so as to be received by the die members 21 during one of the twisting operations of the machine.

There are three distinct twisting operations in the operation of the machine. All of these twisting operations are accomplished by a single stroke of the hydraulically operated actuating lever. Figs. 4 to 7, inclusive illustrate diagrammatically the manner in which the three throws of the crank shaft are produced so that all of the bearings 30, 31 and 32 will be in alignment at the center of the finished crank shaft. The two crank pins 33 and 38 will be in alignment. The two intermediate crank pins 35 and 36 will be in alignment but one hundred and twenty degrees from the crank pins 33 and 38, and the two remaining crank pins 34 and 37, while being in alignment with each other, will be located one hundred and twenty degrees from the other two pairs of crank pins, as illustrated in Fig. 7.

The method and manner of twisting the crank shaft to accomplish this result will be described first so that a clear understanding may be had as to the objectives before a more detailed description is given with respect to the other figures of the drawings. In Fig. 4, it will be noted that the two crank pins 34 and 37 are in alignment, and the three bearings 30, 31 and 32 also are in alignment with each other and lie intermediate the crank pins 34 and 37 and the remaining crank pins. These remaining crank

pins 33, 35, 36 and 38 also are all in alignment with each other before the twisting operation is begun.

The first twisting operation is carried out by rotating certain of the crank pins and bearings about the axis of the crank pins 34 and 31 as a center. Fig. 5 illustrates diagrammatically the appearance of the crank shaft at the end of the first twisting operation, where the two outer crank pins 33 and 38 and the end bearings 30 and 31 have been moved through an arc of sixty degrees about the axis of the crank pins 34 and 37 as a center. During this time the center bearing 32 and the other crank pins 35 and 36 have been held in place by the holding members 10 and 29.

The second twisting operation moves certain of the crank pins and bearings about the axis of crank pins 35 and 36 as a center. In this second twisting operation, the crank pins 35 and 36, and the center bearing 32, remain in place; while the outer crank pins 33 and 38, the end bearings 30 and 31, and the intermediate crank pins 34 and 37 are moved through an arc of thirty degrees so that the result, at the end of the second twisting operation, appears as illustrated diagrammatically in Fig. 6.

The final twisting operation takes place during the second twisting operation and constitutes the movement of the end bearings 30 and 31 back into alignment with the center bearing 32, whereby the result will be as illustrated diagrammatically in Fig. 7.

Summarizing briefly, the operations occur successively as follows:

First twisting operation

During the first twisting operation the inner rotating twisting members 23, 24, 25 and 26 rotate through sixty degrees causing the crank pins 33 and 38, and the end bearings 30 and 31, to be twisted about the axis of crank pins 34 and 37 as a center. The end bearings 30 and 31 are in, or contained by, their dies 21 at the beginning of the first stroke or twist, but are forced or twisted into place within their twisting dies 21 at the end of the first twist.

Second twisting operation

The second twisting operation continues to move the inner rotating twisting members 23, 24, 25 and 26, and moves also the outer rotating twisting members 11, 12, 27 and 28 through an arc of thirty degrees. This movement of the twisting members carries the crank pins 33, 38, 34 and 37 about the axis of crank pins 35 and 36 as a center.

Third twisting operation

The third twisting operation occurs during the second twisting operation. The end bearings 30 and 31 are not contained within their twisting dies 21 until the end of the first twisting operation. The third twisting operation, therefore, constitutes a rotary movement of the twisting dies 21 which carries the end bearings 30 and 31 about the axis of crank pins 33 and 38 as a center to bring these end bearings 30 and 31 back into alignment with the center bearing 32.

Fig. 9 illustrates the upper and lower dies 9 and 8 respectively in closed position after the first twisting operation. The rotation of the twisting dies is preferably carried on hydraulically, and for this purpose a twisting cylinder

39 is provided. The cylinder 39 is adapted to have hydraulic fluid forced therein from the pump 1 to operate a piston. A piston rod 40 is connected to the piston which is arranged in the cylinder 39. The rod 40 is connected pivotally at 41, to a yoke 42 which is secured to the rotating twisting members 23 and 24 of the lower die 8. This pivotal connection, and the formation of the yoke 42, is shown in dotted lines in Fig. 3.

The upper and lower dies are illustrated in their open position in Fig. 8. The inner twisting member 26 of the upper die 9 is a substantially semi-circular member, and may cooperate with the semi-circular twisting member 24 of the lower die 8. The upper and lower twisting members 25 and 23 are similarly arranged to cooperate with each other during the twisting operation.

20 The outer rotating twisting member 28 of the upper die 9 has a configuration substantially like that shown in Fig. 8, being adapted to cooperate with the outer rotating twisting member 12 of the lower die 8.

25 The holding member, or stationary die member, 29 of the upper die 9, is likewise adapted to cooperate with the holding member 10 in the lower die 8. In the normal open position of the upper and lower dies the holding member 29, the inner rotating twisting members 25 and 26, and the outer rotating twisting members 27 and 28, all have their lower faces in a common plane. The respective cooperating holding and twisting members of the lower die 8 also are arranged to have

30 coplanar faces in the normal open position of the upper and lower dies. Suitable recesses in the holding and twisting members of the upper and lower dies are provided to receive the crank shaft. When the upper die is brought downwardly 40 against the lower die, the coplanar faces of the elements constituting the upper dies, which are indicated by the numeral 43, will be brought against the coplanar faces of the cooperating holding and twisting members comprising the lower die, as indicated at 44.

45 Downward movement of the piston rod 40 carries with it the yoke 42 which is secured to the inner rotating twisting dies 23 and 24, so that these twisting dies 23 and 24, will be in the position indicated in Fig. 9. The inner rotating dies 25 and 26 of the upper die will be caused to rotate by cooperating with the twisting members 23 and 24, thereby to assume the position shown in Fig. 9.

50 During the first twisting operation, the inner rotating twisting members 23, 24, 25 and 26 will be the only ones which will move. As stated hereinabove, the end bearing twisting dies 21 do not contain the end bearings 30 and 31 until the 55 end of the first twisting operation. Fig. 19 illustrates the end bearing twisting dies 21, and the position of the end bearings 30 and 31 therein, at the end of the first twisting operation.

The yoke 42 carries a lug 45 thereon, which lug 60 45 is adapted to come against a face 46 of the outer rotating twisting members 11 and 12 in the lower die 8. This lug 45 is shown clearly in Fig. 8, the two dies being separated; and Fig. 9 shows the lug 45 bearing against the face 46.

65 70 Continued downward movement of the piston rod 40, and yoke 42, will then cause a rotation of the outer rotating twisting members 11 and 12 of the lower die because of the lug 45 bearing against the face 46. The end of the twisting operation is 75 illustrated in Fig. 11 wherein the lug 45 is shown

in contact with the face 46, the twisting members 11 and 12 having been rotated through an angle of thirty degrees.

During this second twisting operation, the end bearing twisting dies 21 are rotated about the axis of crank pins 33 and 38 as a center, and this movement of the end bearing twisting dies 21 is controlled by a link 47 actuated by the movement of the inner rotating twisting members 23 and 24. Fig. 12 illustrates the final position of the end bearing twisting dies 21 and the end bearings 30 and 31.

After completion of the final twisting operation, the upper and lower dies 9 and 8 are opened to permit operation of the ejector mechanism which includes the lift-out rods 48 and 49. These rods 48 and 49 are positioned below the end bearings 30 and 31, and are hydraulically actuated to move upwardly and lift the completed crank shaft out of the lower die, as shown in Fig. 13. After removal of the completed crank shaft from the rods 48 and 49, the rods are moved downwardly, and the dies 8 and 9 are again closed. The piston rod 40 is then moved upwardly to return all of the rotating twisting members of both the upper and lower dies to their original position. This completes one cycle of operation, and the two dies then may be opened and another forged crank shaft placed in position to have the twisting operations formed thereon.

As stated above, the details of the hydraulic system have not been illustrated herein, but the operation of the press may be briefly summarized as follows:

The operator will place a forged crank-shaft, with all of the crank pins and bearings in the same plane, into the lower die 8 when the dies are open. The operator then may depress a cycle button, to cause the press to begin its downward stroke. When the upper die has reached the lower die, pressure is built up in the main cylinder of the hydraulic system. After a predetermined amount of pressure has been reached a sequence valve automatically will direct the flow of hydraulic fluid from the pump 7 into the hydraulic cylinder 39. This will cause the piston and its attached piston rod 40 to move downwardly and rotate the inner twisting members 23, 24, 25 and 26, causing crank pins 33 and 38 and end bearings 30 and 31 to swing sixty degrees about the center of crank pins 34 and 37.

This twisting action will thereupon move the end bearings 30 and 31 into their respective twisting dies 21. The piston rod 40 will continue in its downward movement, whereupon the lugs or projections, either on the yoke 42 or on the inner twisting members, will contact the outer rotating twisting members 11 and 12 and cause the inner and outer rotating twisting members to rotate together. This latter rotation of all of the twisting members will cause a twisting of crank pins 33, 38, 34 and 37 about the center of crank pins 35 and 36. Also, during this latter movement and operation, the twisting dies 21 containing the end bearings 30 and 31, will twist the end bearings 30 and 31 about the center of crank pins 33 and 38 and move them into alignment with the center bearing 32.

The twisting stroke is then completed, and the press will open automatically as shown in Fig. 13. During the upstroke of the upper die the lift-out rods 48 and 49 will move upwardly through the bed and raise the completed crank shaft out of the lower die. The crank shaft is then removed and the lift-out rods drop back into the lower dies

5 by the operation of an independent air valve. The press is then closed before another crank shaft is placed therein, and the piston rod is caused to move upwardly to reverse the procedure just described for the purpose of returning all of the twisting members to their original position. The press again opens automatically and is then ready for loading another crank shaft.

Changes may be made in the form, construction and arrangement of parts and the method may be varied within certain degrees herein without departing from the spirit of the invention or sacrificing any of the attendant advantages thereof, provided, however, that such changes fall 10 within the scope of the claims appended hereto.

Having thus described my invention what I claim as new and desire to secure by Letters Patent of the United States is:

1. A crank shaft twisting machine comprising 15 a pair of dies movable to open and closed positions and adapted to receive a crank shaft wherein the bearings and crank pins are all in the same plane, cooperating stationary holding members in said dies adapted to engage and hold the crank shaft, cooperating rotating twisting members in said dies each adapted to engage a different crank pin on the crank shaft for twisting, means operable upon one of the twisting members of one die for rotating said one twisting member and its cooperating twisting member in the other die when the dies are closed thereby twisting the crank pins in said one twisting member out of the planes of the other crank pins and bearings, and means on said one twisting member 20 adapted to cooperate with the other twisting member of the same die for rotating said other twisting member and its cooperating twisting member in the other die after said one twisting member has been rotated through a predetermined arc thereby twisting the crank pins in said other twisting members out of the planes of the remaining crank pins and bearings.

2. A crank shaft twisting machine comprising 25 a pair of dies movable to open and closed positions and adapted to receive a crank shaft wherein the bearings and crank pins are all in the same plane, cooperating stationary holding members in said dies adapted to engage and hold the crank shaft, cooperating rotating twisting members in said dies each adapted to engage a different crank pin on the crank shaft for twisting, means operable upon one of the twisting members of one die for rotating said one twisting member and its cooperating twisting member in the other die when the dies are closed thereby twisting the crank pin in said one twisting member out of the plane of the other crank pins, and means on said one twisting member adapted to 30 cooperate with the other twisting member of the same die for rotating said other twisting member and its cooperating twisting member in the other die after said one twisting member has been rotated through a predetermined arc and during continued rotation of said one twisting member.

3. A crank shaft twisting machine comprising 35 a pair of separable dies adapted to receive a crank shaft wherein the bearings and crank pins are all in the same plane, cooperating holding members in said dies adapted to hold intermediate crank pins of a crank shaft, cooperating rotating twisting members in said dies each adapted to engage a different crank pin on the crank shaft for twisting, means operable upon one of the twisting members of one of the dies for rotating said one twisting member and its cooperating twisting

member in the other die when the dies are closed thereby twisting the crank pin in said one twisting member out of the plane of the other crank pins and bearings, means for rotating the other twisting members after said one twisting member has been rotated through a predetermined arc, and a twisting die for each end bearing of a crank shaft, and means whereby said first named means also positions the ends of a crank shaft within said twisting dies.

4. A crank shaft twisting machine comprising upper and lower dies movable to open and closed positions and adapted to receive a crank shaft wherein the bearings and crank pins are all in the same plane, cooperating holding members in said dies adapted to engage and hold the crank shaft, cooperating rotating twisting members in said dies each adapted to engage a different crank pin on the crank shaft for twisting, means operable upon one of the twisting members of said lower die for rotating said one twisting member and its cooperating twisting member in the upper die when the dies are closed thereby twisting the crank pin in said one twisting member out of the plane of the other crank pins, means for rotating the other twisting member of the lower die and its cooperating twisting member in the upper die during a portion of the rotating movement of said one die, and a twisting die for each end bearing of a crank shaft, and means whereby said first named means also positions the end bearings of a crank shaft within said twisting dies.

5. A crank shaft twisting machine comprising upper and lower dies movable to open and closed positions and adapted to receive a crank shaft therein wherein the bearings and crank pins are all in the same plane, cooperating stationary holding members in said dies to hold certain of the crank pins and bearings of the crank shaft against movement, cooperating inner rotating twisting members in said dies adapted to engage certain of the crank pins of the crank shaft to twist certain of the crank pins of the crank shaft about a predetermined axis, cooperating outer rotating twisting members in said dies adapted to engage certain other crank pins on the crank shaft to twist said certain other crank pins of the crank shaft about a predetermined axis, means operable upon the inner rotating twisting members of one of said dies to rotate the inner rotating twisting members of both of said dies, and means for rotating the outer twisting members of both of said dies after the inner rotating twisting members have been rotated through a predetermined arc.

6. A crank shaft twisting machine comprising upper and lower dies movable to open and closed positions and adapted to receive a crank shaft therein wherein the bearings and crank pins are all in the same plane, cooperating stationary holding members in said dies to hold certain of the crank pins and bearings of the crank shaft against movement, cooperating inner rotating twisting members in said dies operable to twist certain of the crank pins of the crank shaft about a predetermined axis, cooperating outer rotating twisting members in said dies operable to twist certain other crank pins of the crank shaft about a predetermined axis, means operable upon the inner rotating twisting member of the lower die to rotate the inner rotating twisting members of both of said dies, and means for rotating the outer twisting members of both of said dies during a portion of the rotating movement of the inner twisting members.

7. A crank shaft twisting machine comprising upper and lower dies movable to open and closed positions and adapted to receive a crank shaft therein wherein the bearings and crank pins are all in the same plane, cooperating stationary holding members in said dies to hold certain of the crank pins and bearings of the crank shaft against movement, cooperating inner rotating twisting members in said dies operable to twist certain of the crank pins of the crank shaft about a predetermined axis, cooperating outer rotating twisting members in said dies operable to twist certain other crank pins of the crank shaft about a predetermined axis, means operable upon the inner rotating twisting member of the lower die to rotate the inner rotating twisting members of both dies through an arc of substantially 90°, and means for rotating the outer twisting members of both of said dies together with the inner twisting members through substantially the last 30° of said 90°.

8. A crank shaft twisting machine comprising upper and lower dies movable to open and closed positions and adapted to receive a crank shaft therein wherein the bearings and crank pins are all in the same plane, cooperating stationary holding members in said dies to hold the center bearing and the pair of crank pins adjacent said center bearing of the crank shaft against movement when said dies are closed, cooperating inner rotating twisting members in said dies to receive and twist a second pair of crank pins about a predetermined axis, cooperating outer rotating twisting members in said dies to receive and twist a third pair of crank pins about a predetermined axis, means operable upon the inner twisting member of said lower die to rotate the inner twisting members of both dies, and means for rotating the outer twisting members of both dies during a portion of the rotating movement of said inner twisting members.

9. A crank shaft twisting machine comprising upper and lower dies movable to open and closed positions and adapted to receive a crank shaft therein wherein the bearings and crank pins are all in the same plane, cooperating stationary holding members in said dies to hold the center bearing of the crank shaft and the pair of crank pins adjacent thereto against movement when said dies are closed, cooperating inner rotating twisting members in said dies to receive and twist a second pair of crank pins about a predetermined axis, cooperating outer rotating twisting members in said dies to receive and twist a third pair of crank pins about a predetermined axis, means operable to rotate first the inner twisting members and then the outer twisting members, end bearing twisting members adapted to receive and twist the end bearings of the crank shaft about a predetermined axis, the end bearings of the crank shaft being normally positioned out of said end bearing twisting members and movable into said end bearing twisting members during the first rotation of said inner twisting members.

10. A crank shaft twisting machine comprising upper and lower dies movable to open and closed positions and adapted to receive a crank shaft therein wherein the bearings and crank pins are all in the same plane, cooperating stationary holding members in said dies to hold the center bearing of the crank shaft and the pair of crank pins adjacent thereto against movement when said dies are closed, cooperating inner rotating twisting members in said dies to receive and twist a second pair of crank pins about a predetermined axis.

11

mined axis, cooperating outer rotating twisting members in said dies to receive and twist a third pair of crank pins about a predetermined axis, means operable to rotate first the inner twisting members and then the outer twisting members, end bearing twisting members adapted to receive and twist the end bearings of the crank shaft about a predetermined axis, the end bearings of the crank shaft being normally positioned out of said end bearing twisting members and movable 10 into said end bearing twisting members during the first rotation of said inner twisting members, and means for rotating said end bearing twisting

5

12

members after the end bearings have been positioned therein and during the rotation of said outer twisting members.

ALOIS K. NOWAK.
